[57] CLAIM

The ornamental design for a drill guide, as shown and
described.

DESCRIPTION

FIG. 1 is a top plan view of a drill guide embodying our
new design;

FIG. 2 is a left side elevation view thereof, the right side
elevation view being a mirror image of the same;

FIG. 3 is a front elevation view thereof, the rear eleva-
tion view being a mirror image of the same; and

FIG. 4 is a bottom plan view thereof.
